(57) **CLAIM**

The ornamental design for a greeting card with a window as shown and described.

DESCRIPTION

FIG. 1 is a perspective view of a greeting card with a window in a closed position showing my new design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof; and,

FIG. 8 is a perspective view in which the greeting card with a window is in a partially opened position.

The broken lines in the figures show portions of the greeting card with a window which form no part of the claimed design.
